(57) **CLAIM**

The ornamental design for a towel with pocket for head padding, as shown and described.

DESCRIPTION

FIG. 1 is a perspective in-use view of a towel with pocket for head padding showing my new design;

FIG. 2 is a front view thereof;

FIG. 3 is a back view thereof;

FIG. 4 is side view thereof; opposite side view is a mirror image thereof;

FIG. 5 is a top view thereof; and,

FIG. 6 is a bottom view thereof.

In FIGS. 1 and 2, the broken lines showing the environmental structure for purposes of illustrating the towel with pocket for head padding in a condition of use. The broken lines and the structure they depict form no part of the claimed design.
